BOAT HULL FOR PLANING CRAFT

Edward A. McNeil, 14 Park St., and William E. McNeil,
both of Roseland, N.J.; said William E. McNeil as-
signor to said Edward A. McNeil

Filed Dec. 22, 1961, Ser. No. 161,544

9 Claims. (Cl. 114—66.5)

The present invention relates to hulls for boats and the like, and, more particularly, to an improved variable displacement planing hull of the air supported type.

In propelling boats through water a very large percentage of power, which otherwise could be utilized to move the boat forwardly at a greater speed, is wasted by shoving the water aside at the bow to produce a bow spray and at the sides to produce a wake. The side spray generated by a planing surface can have a force of considerable magnitude. The more spectacular and impressive the side spray and wake are, the greater is the waste of power. The magnitude of this wasted power can be appreciated by noting the violent tossing of sizable boats at anchor when comparatively smaller power boats pass by. A conservative estimate is that at least 40% of the propulsion power of the boat is so wasted.

While the wasting of available power by wetted surface friction between the boat hull and the water and by suction drag under the stern of the boat hull has been recognized and has led to the design of better hulls, such designs are not entirely satisfactory with respect to the problem which they purport to solve and serve no useful purpose in minimizing bow spray, side spray and wake to prevent the resulting waste of power.

Accordingly, an object of the present invention is to provide an improved hull for planing craft which greatly minimizes the waste of power caused by generating a bow spray, side spray and a wake and which at the same time greatly reduces wetted surface friction and stern suction.

Another object is to provide such a hull which planes in substantially the same attitude it is in when resting on the water.

Another object is to provide such a hull which has excellent lateral stability.

Another object is to provide such a hull which has excellent longitudinal stability.

Another object is to provide such a hull which is more comfortable to the passengers as the bow spray and side spray which otherwise would be driven into the boat by wind is eliminated.

Another object is to provide such a hull which by reason of its minimum spray and wake is more difficult to detect from land, sea or air and therefore has strategic value for use with military craft.

Another object is to provide such a hull which more fully utilizes a power plant of a given size to propel the boat at a greater speed or to enable the boat to carry a greater load at the same speed.

Another object is to provide such a hull which enables a boat of a given size to be driven more economically by a smaller power plant.

Another object is to provide such a hull which assures its passengers a softer cushioned and less bumpy ride.

Another object is to provide such a hull which by reason of a wide area of positive lifting pressure on its bottom surfaces is less affected by local disturbing water forces to induce pitching or porpoising.

Another object is to provide such a hull wherein its trim is less affected by the shifting of internal weights, passenger load distribution or fuel consumption by reason

of the wide area of positive lifting pressure on its bottom surfaces.

Another object is to provide such a hull whose visible form and contours do not clash with the public's concept of acceptable lines, and which as a result of a deep wide chine line has more useable internal space.

Another object is to provide such a hull whose curved bottom surfaces are self supporting and possess great structural strength, without complex internal bracing.

Another object is to provide such a hull which by reason of its positive lift in the stern area is better able to support heavy outboard motors or inboard-out drives which are normally located at or near the stern.

Another object is to provide such a hull wherein the stern does not squat down to invite swamping by a following sea.

Another object is to provide such a hull which is adapted for use with seaplanes or amphibious craft of civilian or military types.

20 A further object is to provide a hull structure which can be embodied in newly fabricated hulls and can be applied to existing hulls to improve the functioning thereof.

A still further object is to accomplish the foregoing 25 in a simple, practical and economical manner.

Other and further objects of the invention will be obvious upon an understanding of the illustrative embodiment about to be described, or will be indicated in the appended claims, and various advantages not referred 30 to herein will occur to one skilled in the art upon employment of the invention in practice.

In accordance with the present invention, it has been discovered that the foregoing objects can be accomplished by providing a planing hull which comprises a bow, a 35 stern, sides and a bottom, the bottom having chines at the sides thereof, a keel, and a generally concave downwardly facing tunnel on the underside of the bottom between the keel and each of the chines which elements appear to have critical relationships by reason of these 40 arrangements and dimensions.

A preferred embodiment of the invention has been chosen for purposes of illustration and description, and is shown in the accompanying drawings, forming a part of the specification, wherein:

45 FIG. 1 is a side elevational view of a hull in accordance with the present invention.

FIG. 2 is a bottom plan view of the hull.

FIG. 3 is an outline view of a family of curves illustrating half width transverse sections taken through points 50 of the forward or bow zone and the forward portion of the body zone of the hull, and at the stern of the hull.

FIG. 4 is a view similar to FIG. 3 taken through lengthwise spaced points of the body zone of the hull.

FIG. 5 is an outline view of a transverse half width 55 section taken through the body zone of the hull and having dimensional legend thereon from which the data in Table I set forth hereinafter is compiled.

FIG. 6 is an outline view of a transverse half width section illustrating a modified hull.

60 Referring now to FIGS. 1 and 2 of the drawings in detail, a boat hull is shown which generally comprises a bow 25, a stern or transom 26, sides 27, a bottom 28 having a keel 29 at the centerline thereof, and chines 30 defined by the junction of the sides and the bottoms.

65 The hull is divided lengthwise into spaced transverse sections numbered from zero to twenty (bow to stern) to indicate the distance in feet between the bow and each transverse section.

The transverse sections from 0 (bow) to about 5 70 shown in FIG. 3 constitute the forward section of the hull which is generally V-shaped from the bow 25 to

about section 4. The transverse sections from about 6 to 20 (stern) shown in FIGS. 3 and 4 constitute the body zone of the hull. The lower edge of the keel 29 is disposed in a substantially horizontal plane from about section 5 to the stern. This plane is called the keel plane and is the plane from which vertical or height dimensions are taken.

The transverse sections are indicated by broken lines in FIGS. 1 and 2 and are shown in half width outlines in FIGS. 3 and 4 with like reference numerals applied to like sections.

In the forward zone, the sides and bottom diverge aftwise from the bow. The bottom also diverges upwardly and outwardly from each side of the keel and has a concave curvature which becomes more pronounced from just aftwise of the bow towards the body zone (FIG. 3). The sides meet the bottom at an included angle which decreases in magnitude aftwise from about section 3 to about section 8, whereby the chine-like structure become more pronounced and the sides more closely approach the vertical in the aftwise direction.

At about the transverse section 6 where the body zone commences, the curvature of the bottom 28 and the height of the chines 30 above the keel plane is such that the maximum height of the bottom portion above the keel plane slightly exceeds the height of the chines to form a tunnel-like formation in the bottom of the hull at each side of the keel 29 which formations are referred to hereinafter as tunnels 31. The dimension by which the tunnel height exceeds the chine height increases sharply from sections 6 to 8 while the tunnels become somewhat wider (FIGS. 2 and 3).

The tunnels 31 continue to extend aftwise from section 8 to the stern and the height thereof decreases on a slope of about 3° to 4° to the keel plane (FIG. 1). The dimension by which the tunnel height exceeds the chine height now decreases aftwise; and the width of the tunnels (the is, the horizontal distance between keel and the chines) decreases slightly (at a rate of about 10%) in an aftwise direction. Thus, between the section 8 and the stern, the cross-sectional area of the tunnels, which is defined by the curvature of the bottom and a straight line from the keel to the chines (FIG. 4) decreases aftwise, for example, the area at section 8 is about three to four times as great as this area at about the stern.

Preferably, the hull is provided with more or less conventional anti-trip chines 32 extending from about the transverse section 12 to the stern (FIGS. 1 and 4). The presence of these anti-trip chines is disregarded in measuring the chine angles (Table I) at these transverse sections. However, since the anti-trip chines are disposed at an angle of 45° to the horizontal, the chine angle is 45° less than the angle given in Table I when the anti-trip chines are regarded in measuring the chine angles at sections 12 to 20.

When the hull is normally loaded, the keel plane slants forward and the hull is immersed so that the water line WL extends from about section 7 or just aft thereof to the stern (FIGS. 1, 3 and 4). Thus, between about sections 6 and 7 the chines and the tunnels are above the water line, and between sections 8 and about 14 the middle of the tunnels is above the water line but the chines are immersed to provide a sealed tunnel area, whereby air and turbulent water caused by bow spray beginning at about section 3 are scooped from about sections 5 to 7, are fed into the sealed tunnel area commencing at about section 7, and are confined to flow aftwise through the tunnels and exit at the stern. Since the sealed tunnel area decreases aftwise, the air flowing therethrough is compressed so that the entire body zone of the hull practically rides on air to greatly decrease friction drag on the hull.

The portions of the bottom of the hull providing the tunnels 31 have a curvature produced in a beam which is fixed at one end and is deflected by applying a com-

pression force at its other end in a direction towards the fixed end, which curvature is generally elliptical. Such transverse formations have good structural strength.

In FIG. 5, an outline of a half-width transverse section is shown which includes dimensional legend referenced for use in connection with the table of dimensions about to follow, the significance of the legend being explained in the footnotes to the table. As indicated in this view, the base of the keel has a width of one inch in the body zone of the hull.

In order to demonstrate the practical aspects of the present invention, a boat hull having a length of about twenty feet and a nominal beam of about seven feet and nine inches was constructed in accordance with the dimensions set forth in Table I.

Table I

L, feet	KA, degrees	CA, degrees	W, inches	H, inches	TW, inches	TH, inches	CH, inches

20	150	85	42.5	40	36.5	4.6	3.6

L—Distance from bow.

KA—Keel angle (included).

CA—Chine angle.

W—Half width between sides at top.

H—Height of sides above keel plane.

TW—Tunnel width.

TH—Tunnel height (maximum).

CH—Chine height above keel.

WL—Water line begins.

Certain of the dimensions in Table I, particularly the keel and chine angles, are only approximate because they were measured on the constructed hull.

This hull was propelled by a 50 horsepower outboard engine driven at full speed on Barnegat Bay, New Jersey, and attained a speed of about 35 m.p.h. without producing any perceptible bow spray or wake, and planed substantially horizontally, that is, in about the same relative positive it is in when resting on the water with the chines at sections 8 to 20 remaining fully immersed. The hull also had excellent lateral stability, particularly on sharp turns, and had excellent maneuverability.

Furthermore, the hull did not pound in rough water as the deep chines provide additional variable displacement cushioning and provided a dry ride for its passengers. The hull did not ride bow high to obstruct visibility nor did the stern squat down to invite swamping.

It is believed that the foregoing performance is due to the construction and arrangement of the keel, chines and tunnels whereby turbulent water and air is scooped and deflected into the tunnels and a minimum of water is permitted to escape to produce a bow spray which wastes power. The air is entrapped in the tunnels and is compressed multi-stagewise by successive waves and surface foaming as it flows towards the stern to provide a cushion of air for lifting the hull and on which the hull rides to reduce surface friction between its bottom and the water and to also eliminate suction drag under the stern.

Furthermore, it should be noted that the chine angles CA are sharpest at about section 7 where they first enter the water and gradually decrease as they approach the stern (FIGS. 3 and 5, Table I). These angles thereby provide a knifelike entrance to allow forward motion of

the hull with a minimum of disturbance of the water, and provide a very gradual change of displacement in rough water with a resulting snubbing action as the water is displaced transversely towards the center of the tunnels which makes for an exceptionally smooth ride. Also, the sharpness of the angles where the chines first enter the water provides excellent tracking and unusual lateral stability which aids in holding a straight true course in wind and rough water. Such deep forward tracking provides remarkable stability on tight fast turns and provides in effect a pivot point about which the powered stern can be steered.

Still further, it is believed that one of the most important features contributing to overall efficiency of the hull is that the gradual and uniform flattening of these angles maintains a constant, continual and uniform change in flow direction of the adjacent water particles from which the dynamic hull lift is obtained. Thus, by imparting a constant change of direction it is possible to effectively spread the lift over the entire bottom area in the body zone, and, by controlling air and water flow in the foregoing manner, a positive pressure can be produced at the stern area where heretofore a considerable suction drag has been experienced with conventional hulls. As a result, the hull will not appreciably pitch or roll due to disturbing forces such as rough water, wind and load shift.

The twin tunnels assure an ample supply of undisturbed water in which a single propeller can operate to drive the hull at a high speed, whereby twin propellers are not required as in the case of catamarans or twin hulls. The hull in accordance with the present invention is ideal for conventional outboard motors, turbo jet drives and for inboard-outdrive power plants where the drive shaft extends through the transom.

In FIG. 6, a modified form of hull is shown wherein the tunnels 31 are subdivided into a number of substantially parallel lengthwise extending flutes 33 having a concave contour to provide a group of small tunnels within the tunnels 31 which are separated by small keel-like portions or steps 34 adapted to further improve the stability of the hull particularly in extremely rough seas. These small tunnels and steps are dimensioned to follow the general outline of the hull structure shown in FIGS. 3 and 4. Preferably, these tunnel-like sections 33 have a width about four to about six times greater than their depth.

While the present invention has been described in connection with newly fabricated hulls, it will be understood that it can be applied to hulls already in use. For example, a hull having a V or rounded contour adjacent its keel may be modified by attaching a supplementary form to the underside which provides a deep chine and a half tunnel section laterally outward of the contours along the keel, whereby the hull is modified to embody the chine and tunnel structure described herein.

From the foregoing description, it will be seen that the present invention provides a simple, practical and efficient hull design for the purposes indicated herein.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

We claim:

1. A hull comprising a bow, a stern, sides, a bottom having a keel at the center line thereof, and chines defined by the junction of said sides and said bottom, said hull having a forward zone wherein said sides and said

bottom diverge aftwise and diverge upwardly and outwardly from said keel, said hull having a body zone extending aftwise from said forward zone to said stern wherein said bottom has an identical tunnel of generally elliptical curvature between said keel and the chine at each side of the hull, the length of said body zone being about three times greater than the length of said forward zone and the cross-sectional area of said tunnels at a forward section of said body zone being about three times greater than at the stern end of said tunnels and said hull having a beam about equal in width to the length of said forward zone, the foremost transverse sections of said body zone having the tunnels and chines positioned above the water line of the hull to provide scoops and the immediately aftwise following sections of said body zone having the chines positioned to extend below the water line of the hull and having at least a substantial portion of the tunnels above the water line of the hull for receiving air and turbulent water from the scoops, said tunnels decreasing in height and width from the scoops to said stern to entrap and confine air and water between said keel and said chines and to allow the air and water to exit at said stern end of said tunnels.

2. A hull according to claim 1, where said keel extends further downwardly than said chines throughout its entire lengthwise extent and is disposed in a substantially horizontal plane from about the stern to about the middle of said forward zone, the maximum height of said tunnels at any given transverse section being nearer said chines than said keel.

3. A hull according to claim 1, wherein said tunnels at about the foremost section of said body zone have a horizontal width about two times greater than the vertical height thereof and said tunnels at immediately aftwise sections in said body zone have a horizontal width about three times greater than the vertical height thereof.

4. A hull according to claim 3, wherein said tunnels at the stern portion of said body zone have a horizontal width at least about six times greater than the vertical height thereof.

5. A hull according to claim 2, wherein the height of said chines above the said keel in said body zone decreases in an aftwise direction.

6. A hull according to claim 5, wherein the vertical height of said tunnels slightly exceeds the height of said chines above said keel at the stern, and the vertical height of said tunnels exceeds the vertical high of said chines in a forward section of said body zone by a dimension about five times greater than at said stern.

7. A hull according to claim 6, wherein the vertical height of said tunnels slightly exceeds the height of said chines in the foremost section of said body zone.

8. A hull according to claim 1, wherein said tunnels are subdivided crosswise into lengthwise extending small tunnel-like sections.

9. A hull according to claim 8, wherein said tunnel-like sections are generally concave and a step is provided between adjacent tunnel-like sections.
